US00D696254S

(12) **United States Design Patent**
Groene et al.

(10) **Patent No.:** **US D696,254 S**
(45) **Date of Patent:** **** Dec. 24, 2013**

(54) **ELECTRONIC TABLET WITH INPUT DEVICE**

(71) Applicant: **Microsoft Corporation**, Redmond, WA (US)

(72) Inventors: **Ralf Groene**, Kirkland, WA (US); **Hua Wang**, Sammamish, WA (US); **Anthony Reed**, Sammamish, WA (US); **Katherine Bailey**, Seattle, WA (US); **James Alec Ishihara**, Bellevue, WA (US); **Jan Raken**, Seattle, WA (US)

(73) Assignee: **Microsoft Corporation**, Redmond, WA (US)

(**) Term: **14 Years**

(21) Appl. No.: **29/448,267**

(22) Filed: **Mar. 11, 2013**

Related U.S. Application Data

(63) Continuation of application No. 29/422,121, filed on May 16, 2012, now Pat. No. Des. 678,272.

(51) **LOC (9) Cl.** **14-02**

(52) **U.S. Cl.**

USPC **D14/345**; D14/341

(58) **Field of Classification Search**

USPC D14/341-347, 336, 337, 371, 374, 138, D14/496, 320, 331, 333, 392, 455; D10/65; 345/901, 104, 133, 156, 168, 173; 348/180, 184, 325, 739, 373, 376; 385/88; 710/62; 455/575.3, 575.1; D19/60; 361/679.27; 178/18.03; 434/317

(57) **CLAIM**

The ornamental design for an electronic tablet with input device, as shown and described.

DESCRIPTION

FIG. 1 is a front isometric view of an electronic tablet with input device showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken line showing of various features on the electronic tablet with input device represents portions of the electronic tablet with input device which form no part of the claimed design.

1 Claim, 6 Drawing Sheets
